CLAIM

The ornamental design for a dispensing closure of glove dispensing container, as shown and described.

DESCRIPTION

FIG. 1 is a front perspective view of a dispensing closure of a glove dispensing container;

FIG. 2 is a front view thereof;

FIG. 3 is a rear view thereof;

FIG. 4 is a left side view thereof;

FIG. 5 is a right-side view thereof;

FIG. 6 is a top view thereof; and,

FIG. 7 is a bottom view thereof.

The present application is directed to the shape and configuration of a dispensing closure of a glove dispensing container.

The shading lines in the views are not features of the design but are utilized to illustrate a surface of the dispensing closure and surfaces of the glove dispensing container, and are not intended to indicate surface decoration.
